DRIP CATCHER

Vito A. Pugliese, Buenos Aires, Argentina

Application September 27, 1955, Serial No. 536,847

4 Claims. (Cl. 135—48)

The present invention relates to a device for catching water drippings and is particularly adapted for attaching to umbrellas.

When an umbrella is used as a protection against rain in the customary manner the outer surface of the cloth collects a quantity of water which is more or less absorbed, according to the capillarity of the cloth, and this water runs down to the lowest point as soon as the umbrella is closed and then drips upon the floor until such time as the user is able to place the wet umbrella in some suitable receptacle to catch the remaining rain water dripping from same.

It is scarcely necessary to draw attention to the inconvenience of having to dry and repolish the floor after same has been wetted in this fashion, and there is the additional chore of eventually having to empty whatever receptacle may have been used as a collector.

The object of the present invention is that of providing a device of simple construction, light weight and easy application, which radially removes the abovementioned inconveniences, as, by means of this device, it is only necessary to invert the wet umbrella from its operative position and close same, when the rain water runs down and is collected in a small container, which is attached by frictional pressure to the ferrule end of the umbrella stick, the construction of said container being the characterizing novelty of this invention, which furthermore comprises discharging means in suitable position for removing the rain water collected in the container.

The characteristic construction of the device consists of a hollow body with concentric double walls, united at one end and provided at that end with a removable plug for emptying the device.

The exterior wall has an open opposite end, provided with a cup-shaped interior flange having a flaring ring at its lower edge, and the interior wall also has an open end opposite to the end that is joined to the exterior wall, said open end being provided with a mushroom-shaped flange, adjacent, but spaced away from, the lower edge of said cup-shaped flange of the outer wall, whereby the drops etc., of water running down the umbrella stick and/or the interior of said cup-shaped flange are detoured into the body of the collecting vessel formed by the union of the two walls.

The flaring ring at the lower end of the said cup-shaped flange is provided to act as a retaining pocket for any water collected in the container that would otherwise be thrown out in the event of an accidental reversal of the umbrella before emptying said container.

For easy comprehension of this invention, a preferred embodiment is illustrated in the accompanying drawings, but it is understood that the invention is not limited thereby, but is susceptible of changes in form and detail within the scope of the appended claims.

Fig. 1 is a vertical section through the axis of the device in operative position, adapted and fixed to an umbrella for collecting the water dripping from same.

Fig. 2 is a perspective view of the device in use when

2

attached to an umbrella. In both figures the same reference numbers indicate the same or equivalent parts.

From the illustrations it will be seen that the two walls 1 and 2 are joined by the bottom wall 3, which is provided with an outlet and a removable plug 4, for draining the collector.

The exterior wall 2, open at the upper end, has a cup-shaped interior flange 5, provided with a collar 6, and a flaring ring 7, at its lower edge, said collar 6 allowing free and unobstructed passage for the stick of the umbrella 8, shown by dotted lines in Fig. 1. The interior wall 1 is adapted to receive and hold the umbrella stick 8 tightly and its upper, open end which is of mushroom shape is concentric with, but spaced away from, the said collar 6, of the exterior wall 2.

The device is fixed to the free or ferrule end of an umbrella stick by hand pressure until the stick is firmly held by frictional contact along the surface of the inner wall 1.

Once the device has been firmly fixed on the umbrella end, it is intended to remain there permanently.

After making use of the umbrella in the customary manner, same may be closed and inverted as usual, when the excess rain water that has not been actually absorbed by the cloth will run down and be caught in the cup 5, and then pass through the collar 6, and fall on the mushroom-shaped flange 9, to drop finally into the space between the two walls of the container, where it will collect above the level of the outlet plug 4, which can be made use of at any suitable moment for emptying the container.

Should the umbrella be inverted accidentally whilst some water still remains in the collector, the flaring ring 7 and the mushroom-shaped flange 9 will tend to reduce, if not prevent, any quantity of water from escaping through the cup 5.

I claim:

1. Drip catcher adapted to be attached to the tip of an umbrella as described, comprising a cylindrically shaped, double walled container, said walls being concentrically spaced apart and united at one end, the opposite end of said outer wall being cup-shaped and provided with a central opening, the said inner wall having a mushroom-shaped flange opposite and spaced away from the central opening of the said cup-shaped end of said outer wall.

2. Drip catcher adapted to be attached to the tip end of an umbrella as described, consisting of a cylindrically shaped, double walled container, said walls being concentrically spaced apart and united at one end by a bottom wall extending between the inner and outer walls of said container, the opposite end of said outer wall being cup-shaped and provided with a central opening and the said inner wall having a mushroom-shaped flange opposite and spaced away from the central opening of the said cup-shaped end of said outer wall; said bottom wall being provided with an outlet opening suitably positioned therein and a removable closure for said outlet opening.

3. Drip catcher adapted to be attached to the tip end of an umbrella as described, consisting of a cylindrically shaped, double walled container, said walls being concentrically spaced apart and united at one end, the opposite end of said outer wall being cup-shaped and provided with a central opening, the said inner wall having a mushroom-shaped flange opposite and spaced away from the central opening of the said outer wall; said cup-shaped portion of said outer wall being provided with a cylindrically shaped collar at its lower end extending around said opening, and the outer edge of said collar being provided with a flaring ring.

4. A drip catcher adapted to be attached to the tip end of an umbrella, comprising a cylindrically shaped con-

tainer having spaced walls providing an inner sleeve extending upwardly toward the open end of the container, a cup-shaped flange extending inwardly from the upper end of said container and having a central collar extending in a direction toward said sleeve, said collar and sleeve being provided with opposed flanges extending in a direction toward the outer wall of said container, said flanges being spaced and arranged to permit drippings from the umbrella to pass therebetween and into the con-

tainer, and a closure plug removably mounted in a drain opening in the lower end of said container.
